UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,192,934.

Specification of Letters Patent.

Patented Aug. 1, 1916.

Application filed July 21, 1914. Serial No. 852,251.

To all whom it may concern:

Be it known that I, WILLIAM J. ROCHE, a resident of Meadville, in the county of Crawford and State of Pennsylvania, have ⁵ invented a new and useful Improvement in Garment-Stays, of which the following is a specification.

This invention relates to garment stays, and particularly to wire stays for use in corsets and other like articles of wearing apparel.

The object of the invention is to provide a new and improved stay which can be readily manufactured, which contains a long length ¹⁵ of wire in a stay of given dimensions, which is reinforced along its middle line, in which the wear is distributed over a long length of wire, and which avoids liability of the stay taking a permanent set on short bends.

²⁰ The invention comprises the stay herein-after described and claimed.

In the drawings, which represent one embodiment of the invention, the single view shown is a plan view on an exaggerated scale ²⁵ of one face of the stay.

The stay shown in the drawings is formed of wire, and preferably of a single wire 1, which is bent back and forth across the stay to form a series of transversely extending ³⁰ crossing portions 2 and two rows of loops or eyes lying along the edges of the stay. These loops or eyes, as shown, are of two kinds, reëntrant loops 3 and return loops 4. The reëntrant loops are formed by bending ³⁵ portions of the wire inwardly toward the center line of the stay, leaving the loops open toward the outer edges thereof. The return loops 4 are formed by bending one of the edge loops backwardly upon itself at one ⁴⁰ side toward one end of the stay and toward its center line.

The edge loops may be arranged in any suitable manner, but in the form shown, the return and reëntrant loops are spaced alternately along the edges of the stay. For example, there is a return loop on one side and a reëntrant loop on the other side of one end of each of the crossing portions 2 of the wire. Preferably also, each of the crossing portions ⁴⁵ is connected at one end to a return loop 4 and at its other end to a reëntrant loop 3, and in the form shown the loops are arranged in pairs, the loops of each pair being spaced directly opposite each other. As ⁵⁰ shown, each reëntrant loop is opposed by a

return loop and the loops of each pair may overlap each other to any suitable degree along the middle line of the stay, as shown at 5, which reinforces the stay against bending stresses, particularly in the flatwise direction. ⁶⁰

The stay described is simple and can be readily manufactured. It is very resilient and flexible and contains a long length of wire in a stay of given dimensions, so that ⁶⁵ it has a long life and is not liable to take a permanent set under short bends.

What I claim is:

1. A garment stay, comprising wire bent back and forth to form a series of edge loops ⁷⁰ and connecting crossing portions, part of the edge loops being reëntrant and part returned toward the center line of the stay.

2. A garment stay, comprising wire bent back and forth to form a series of edge ⁷⁵ loops and connecting crossing portions, the loops along the edges of the stay being alternately reëntrant and returned toward the center line of the stay.

3. A garment stay, comprising wire bent ⁸⁰ back and forth to form a series of edge loops and connecting crossing portions, part of the edge loops being reëntrant and part returned toward the center line of the stay, said loops being arranged in pairs with the reëntrant and returned loops opposing each other on opposite edges of the stay. ⁸⁵

4. A garment stay, comprising wire bent back and forth to form a series of loops and connecting crossing portions, part of the ⁹⁰ edge loops being reëntrant and part returned toward the center line of the stay, said loops being arranged in pairs with the reëntrant and returned loops opposing each other on opposite sides of the middle line of the stay, opposing loops overlapping each other along the middle line of the stay. ⁹⁵

5. A garment stay, comprising wire bent back and forth to form a series of reëntrant and returned loops lying on opposite sides ¹⁰⁰ of the middle line of the stay and connected by crossing portions of the wire, the loops on opposite sides of the middle line of the stay overlapping each other along the middle line thereof. ¹⁰⁵

6. A garment stay, comprising wire bent back and forth to form a series of returned and reëntrant loops spaced uniformly along the edges of the stay and alternating with each other. ¹¹⁰

7. A garment stay, comprising wire bent back and forth to form a series of alternately disposed reëntrant and returned loops lying along the edges of the stay and connected by crossing portions of the wire, the loops along opposite edges of the stay being disposed opposite to each other.

8. A garment stay, comprising wire bent back and forth to form a series of alternately disposed reëntrant and returned loops

connected by crossing portions of the wire and being disposed opposite to each other and overlapping each other along the middle line of the stay.

In testimony whereof, I have hereunto set my hand.

WILLIAM J. ROCHE.
